CLAIM

We claim an ornamental design of an in line smart print module including a display, as shown and described.

DESCRIPTION

FIG. 1 is a rear right perspective view of an in line smart print module including a display showing our new design, the back is not part of the claimed design;

FIG. 2 is a rear left perspective view thereof;

FIG. 3 is a top view thereof; and,

FIG. 4 is a right perspective view thereof.

1 Claim, 4 Drawing Sheets
